Primary Examiner — Susan Bennett Hattan*Assistant Examiner* — Rebecca Tsehay(74) *Attorney, Agent, or Firm* — Erickson Kernell IP, LLC(57) **CLAIM**

The ornamental design for a lighter, as shown and described.

DESCRIPTION

FIG. 1 is a perspective view of the lighter in accordance with the present invention;

FIG. 2 is a top plan view of the lighter shown in FIG. 1; FIG. 3 is a front elevation view of the lighter shown in FIG. 1, the rear being a mirror image thereof;

FIG. 4 is a left side elevation view of the lighter shown in FIG. 1;

FIG. 5 is a right side elevation view of the lighter shown in FIG. 1; and,

FIG. 6 is a bottom plan view of the lighter shown in FIG. 1. The broken lines in the drawings depict portions of the lighter that form no part of the claimed design.
